UNITED STATES PATENT OFFICE.

SYLVESTER H. HUNT, OF MILWAUKEE, WISCONSIN.

PRESSURE-CONTROL APPARATUS.

Application filed August 2, 1922. Serial No. 579,197.

To all whom it may concern:

Be it known that I, SYLVESTER H. HUNT, a citizen of the United States, residing at Milwaukee, in the county of Milwaukee and 5 State of Wisconsin, have invented certain new and useful Improvements in Pressure-Control Apparatus, of which the following is a specification.

The present invention relates to means 10 for automatically maintaining a substantially zero pressure of the gases of combustion above the fire within a boiler furnace or other apparatus in which the control of pressure is desirable.

15 The object is to provide an apparatus that is exceedingly sensitive to the variations in pressure and quick acting in the operation of the governing mechanism for controlling such pressure.

20 To that end heat instead of pressure is employed to correct the pressure condition within the furnace, so as to cause a substantially immediate operation of the control mechanism. This has proven by actual demonstration to be quicker than that type in 25 which pressure is employed as the actuating means for the initial control device.

In the accompanying drawings:—

Figure 1 is a view diagrammatic in its 30 character of a well-known type of steam boiler and furnace with the pressure control mechanism in place thereon,

Figure 2 is a view partly in front elevation and partly in section of the controlling 35 member,

Figure 3 is a longitudinal sectional view at right angles to Figure 2.

In the embodiment disclosed a water tube boiler 4 is employed, having a furnace 5 and 40 a stack 6 for the outlet of the products of combustion. In this stack is arranged a damper 7 for controlling the draft and obviously controlling the pressure of the gases in the furnace 5.

45 Mounted in one of the side walls of the furnace is an open-ended tube 8 that is in free communication with the furnace above the fire, and has its outer end in open communication with the outside atmosphere. A 50 collar 9 is threaded on the outer end of the tube 8, and is surrounded by a hood 10 having inset internal lugs 11 that fit upon the collar and space the end wall 12 of said hood from the end of the collar, leaving an 55 open passageway 13 from the inner end of

the collar 9 rearwardly to the atmosphere, as indicated by the arrows in Figure 3. The end wall 12 of the hood may be provided with a peep opening covered by a glass 14 that is held in place by a retaining ring 15, 60 so that a view through the tube and into the furnace can be obtained.

Surrounding the collar 9 and located within the hood 10 is a thermostatic ring 16 which may be of any desired or well-known 65 structure, this ring having one end fastened, as shown at 17 to the collar. Its other end carries a bracket 18 that extends outside the hood. This hood furthermore is provided in one side with chambers 19 and 20 having 70 communication through a port 21. One of these chambers is adapted to receive fluid under pressure, preferably, air, from a pipe 22 connected thereto, and this fluid can obviously pass through the port 21 into the other chamber 20. The amount of air, however, is controlled by a suitable needle valve 23 that enters the port 21. A supply pipe 24 leads from the chamber 20 to suitable means for operating the damper 7. Thus in 75 the embodiment shown in Figure 1, a motor diaphragm 25 is suitably mounted on the boiler structure and to the same is connected the pipe 24. Lever mechanism 26 operated by said motor diaphragm is connected to the 80 damper 7. The chamber 20 is furthermore provided with a vent port 27 opening through a nipple 28, and this nipple is controlled by a valve 29 adjustably mounted on the bracket 18. 85

It will be understood that the conduit or tube 8 has its inner end at or near the place where a zero pressure or so-called "balanced draft" is desired within the furnace, and it will be evident that if pressure occurs in said furnace there will be an outflow of the heated gases through the conduit 8 and hood 10 past the thermostatic ring, as indicated by the arrows in Figure 3. As a consequence the ring will be heated 95 and expanded, thereby moving the valve 29 away from the nipple 28. Assuming that fluid under pressure is in the pipes 22 and 24, and that the motor diaphragm 25 is in an expanded position with the damper 7 100 closed, the relief of the fluid through the nipple 28 will permit the collapse of the diaphragm 25, thereby opening the damper 7 and relieving the pressure since the products of combustion can then flow more freely 105 110

from the stack 6. On the other end, if negative pressure occurs in the furnace atmospheric air will flow inwardly through the hood 10 and conduit 8 into the furnace. 5 This will cool the thermostatic ring 16, causing it to contract and thereby seat the valve 29 upon the vent nipple 28. Pressure will consequently build up immediately in the pipe 24, causing the operation of the motor 10 diaphragm to close the damper 7. It will thus be evident that the degree of opening or closing of the damper is in proportion to the time either hot gas or cool air is passing over the thermostat, and due to the 15 very small amount of pressure required to force the heated or cold gases over the thermostat, the event of pressure change within the furnace is transmitted to the damper more quickly than is the case where direct pressure is employed for actuating the parts. 20

From the foregoing, it is thought that the construction, operation and many advantages of the herein described invention will be apparent to those skilled in the art, 25 without further description, and it will be understood that various changes in the size, shape, proportion and minor details of construction may be resorted to without departing from the spirit or sacrificing any of the advantages of the invention. 30

Having thus fully described my invention, what I claim as new, and desire to secure by Letters Patent, is:—

1. In apparatus of the character set forth, 35 the combination with a furnace having an outlet, of a damper for controlling the escape of the products of combustion through said outlet, means for operating the damper, including a heat-actuated controlling element, and means governed by the pressure in the furnace for supplying heat from the furnace to the heat-actuated element and removing it therefrom. 40

2. In apparatus of the character set forth, 45 the combination with a furnace having an outlet, of means for controlling said outlet, a passageway communicating with the furnace and allowing the influx and effluence of fluids of different temperature, a device 50 in heat-transferring relationship to the said fluids and actuated by a change in temperature, and mechanism controlled by said device for operating the outlet controlling means. 55

3. In apparatus of the character set forth, 60 the combination with a furnace having an outlet, of means for controlling said outlet, a passageway communicating with the furnace and allowing the influx and effluence of fluids of different temperature, a thermostat in heat-transferring relationship to the 65 said fluids and actuated by a change in temperature, and mechanism controlled by said thermostat for operating the outlet controlling means. 65

4. In apparatus of the character set forth, the combination with a furnace having an outlet, of means for controlling said outlet, a passageway communicating with the furnace and allowing the influx and effluence of 70 fluids of different temperature, a thermostat in said passage, and mechanism controlled by said thermostat for operating the outlet controlling means. 75

5. In apparatus of the character set forth, the combination with a furnace having an outlet, of means for controlling said outlet, a passageway communicating with the interior of the furnace and with the outside atmosphere and permitting the inflow of the latter and the outflow of the heated furnace gases, a thermostat in heat transferring relation to the air or gases flowing through the passageway, and operating mechanism for the outlet controlling means controlled by the thermostat. 80

6. In apparatus of the character set forth, the combination with a furnace having an outlet, of means for controlling said outlet, a passageway communicating with the interior of the furnace and with the outside atmosphere and permitting the inflow of the latter and the outflow of the heated furnace gases, a thermostat in heat-transferring relation to the air or gases flowing through the 95 passageway, fluid-actuated mechanism for operating the outlet controlling means, and means actuated by the thermostat for controlling the fluid for actuating said mechanism. 100

7. In apparatus of the character set forth, the combination with a furnace having an outlet, of means for controlling said outlet, a passageway communicating with the interior of the furnace and with the outside atmosphere and permitting the inflow of the latter and the outflow of the heated furnace gases, a thermostat in heat-transferring relation to the air or gases flowing through the 105 passageway, fluid actuated mechanism for operating the outlet controlling means having a vent port, and a closure for said port operated by the thermostat. 110

8. The combination with a chamber and means for creating pressure therein, of a device for controlling said pressure, actuating mechanism for said device including an initial controlling element comprising a heat-actuated element, and means governed by the difference in pressure in said chamber for 115 respectively supplying heat to the heat actuated element and abstracting heat from said heat-actuated element. 120

9. The combination with a conduit open to the alternate flow of fluids of different temperatures respectively in opposite directions, of a heat-actuated element operable in opposite directions and in heat transferring relation to the fluids passing in opposite directions through the conduit and oppositely op- 125 130

erated by the heat of the fluids flowing in opposite directions, and controlling means operated by said heat-actuated element.

10. The combination with a conduit open 5 to the alternate flow of fluids of different temperatures in opposite directions, and comprising a pipe and a hood encircling the pipe, in communication therewith and open to the free flow of fluid in opposite directions therethrough, and mechanism for controlling the opposite flow of such fluids including an oppositely operating thermostatic element in the hood operated in one direction by the heat of the fluid flowing in one 10 direction and in the opposite direction by the heat of the fluid flowing in the opposite direction.

11. The combination with a pipe, of a hood surrounding and in communication

therewith and open to atmosphere, a thermostatic ring in the hood around the pipe, a fluid conduit connected with the hood, and a valve for said fluid conduit actuated by the ring.

12. The combination with a pipe, of a collar fixed upon one end thereof, a hood having spaced internal lugs mounted on the collar, a thermostatic ring surrounding the collar within the hood, a fluid chamber on the hood having a vent, and a valve controlling 20 the vent and operated by the ring.

In testimony whereof, I affix my signature in the presence of two witnesses.
